US0D1049300S

(12) **United States Design Patent** (10) **Patent No.:** **US D1,049,300 S**
(45) **Date of Patent:** **** Oct. 29, 2024**

(54) **FLY TRAP**

(71) Applicant: **Shenzhen Kaiyuan Ark Technology Co., Ltd.**, Guangdong (CN)

(72) Inventor: **Wenzhen Cai**, Guangdong (CN)

(**) Term: **15 Years**

(21) Appl. No.: **29/926,418**

(22) Filed: **Jan. 30, 2024**

(51) LOC (14) Cl. **22-06**

(52) U.S. Cl.

USPC **D22/122**

(58) **Field of Classification Search**

(57) **CLAIM**

The ornamental design for a fly trap, as shown and described.

DESCRIPTION

FIG. 1 is a front, right, top perspective view of a fly trap, showing my new design;

FIG. 2 is a rear, left, bottom perspective view thereof;

FIG. 3 is a rear, right, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The dashed broken lines in the figures are for the purposes of illustrating portions of the fly trap that form no part of the claimed design.

1 Claim, 9 Drawing Sheets
